UNITED STATES PATENT OFFICE

167,272

GOBLET OR SIMILAR ARTICLE OF
STEMWARE

William P. Morrison, Mount Pleasant, Pa., assignor to Bryce Brothers Company, Mount Pleasant, Pa., a corporation of Pennsylvania

Application June 6, 1951, Serial No. 15,433

Term of patent 3½ years

(Cl. D36—8)

To all whom it may concern:

Be it known that I, William P. Morrison, a citizen of the United States, residing at Mount Pleasant, county of Westmoreland, in the State of Pennsylvania, have invented a new, original, and ornamental Design for a Goblet or Similar Article of Stemware, of which the following is a specification, reference being had to the accompanying drawing, forming a part hereof.

Figure 1 is a top plan view of a goblet, showing my new design;

Figure 2 is a side view in elevation;

Figure 3 is a side view in elevation taken with the article turned 45° with respect to the position of Figure 2; and

Figure 4 is an isometric view thereof.

The dominant features of my design are rep-

resented by the portions drawn in full lines as shown.

I claim:

The ornamental design for a goblet or similar article of stemware, as shown and described.

WILLIAM P. MORRISON.
